UNITED STATES PATENT OFFICE.

AURA J. SANDERS, OF CEDAR SPRINGS, MICHIGAN.

PEN OR PENCIL ATTACHMENT.

1,345,962.

Specification of Letters Patent.

Patented July 6, 1920.

Application filed February 28, 1917. Serial No. 151,542.

To all whom it may concern:

Be it known that I, AURA J. SANDERS, a citizen of the United States, residing at Cedar Springs, in the county of Kent and 5 State of Michigan, have invented certain new and useful Improvements in Pen or Pencil Attachments; and I do hereby declare the following to be a full, clear, and exact description of the invention, such as 10 will enable others skilled in the art to which it appertains to make and use the same.

This invention relates to a pen or pencil attachment and has for one of its objects the provision of a device of this character, 15 whereby the writing end of the pen or pencil may be illuminated, making the device especially useful for writing during night time.

Another object of this invention is the 20 provision of a cylindrical casing having means for connecting it to a pen or pencil, in which is mounted a battery and an electric lamp, whereby upon illuminating the electric lamp by the battery, the writing 25 end of the pen or pencil will be illuminated and also the article which is being written upon.

A further object of this invention is the 30 provision of an arm formed upon the casing and having its forward end curved downwardly and flared to form an electric lamp socket to receive the electric lamp so as to position the same adjacent the writing end 35 of the pen or pencil.

A still further object of this invention 40 is the provision of a pen or pencil attachment of the above stated character, which shall be simple, durable and efficient, and which may be manufactured and sold at a comparatively low cost.

With these and other objects in view, as 45 will become more apparent as the description proceeds, the invention consists of certain novel features of construction, combination and arrangement of parts as will be hereinafter more fully described and claimed.

For a complete understanding of my invention, reference is to be had to the following description and accompanying drawing, 50 in which:

Figure 1 is a longitudinal sectional view of a pen or pencil attachment, constructed in accordance with my invention,

Fig. 2 is a transverse sectional view 55 taken on the line 2—2 of Fig. 1,

Fig. 3 is a detail sectional view illustrating a switch for controlling the electric circuit to the electric lamp.

Referring in detail to the drawing, the 60 numeral 1 indicates a substantially cylindrical casing having one end closed by a cap 2. Mounted within the casing 1 is a pair of dry cells or batteries 3 connected together by a contact 4. One of the batteries 65 is grounded to the casing 1 by a contact 5 carried by the forward end of the casing. Formed upon the upper forward end of the casing 1 is a hollow arm 6, which has its forward end inclined downwardly as shown 70 at 7 and flared to form a lamp socket 8 in which is seated an electric lamp 9.

The upper rear end of the casing 1 is provided with an elongated slot 10, to slidably receive a switch 11 having formed thereon, 75 a handle 12, which is disposed exteriorly of the casing for sliding the switch forwardly and rearwardly within the casing. A contact 13 is formed upon the switch 11 and is adapted to engage one of the batteries. 80 A wire 14 is connected to the switch 11 and to the electric lamp 9, whereby upon operating the switch 11, the contact 13 will move in engagement with the batteries and complete an electric circuit to the electric 85 lamp 9.

A band 15 surrounds the casing 1 intermediate its ends and has formed thereon, an arm 16 having one end bent to form a portion of a clamp as shown at 17. A pair 90 of relatively spaced ears 18 are formed upon the arm 16 between which is pivoted the other half of the clamp as shown at 19. Formed upon the portion of the clamp 19 is a handle 20 for the purpose of moving 95 the curved members of the clamp apart so that they may receive a pen or pencil as illustrated in Fig. 1, thus the device is disposed directly above the pencil and the downwardly curved end 7 of the arm 6 disposes the electric lamp 9 at a point adjacent the writing end of the pen or pencil so that the article on which is being written 100 will be efficiently illuminated upon moving the contact 13 in engagement with the 105 battery by the switch 11.

While I have shown and described the preferred embodiment of my invention, it

will be understood that minor changes in construction, combination and arrangement of parts may be made without departing from the spirit and scope of the invention.

5 What is claimed is:

A pen or pencil attachment comprising a cylindrical casing having one end closed and a slot adjacent its other end, means securing the casing to a pen or pencil, a 10 tubular arm formed on the closed end of the casing and in communication with the interior thereof, an electric lamp secured in the end of said arm, a battery in said casing and having one pole 15 thereof, electrically connected to the casing, a removable cap closing the open end

of the casing, an insulated contact arm 20
slidable in said slot, a handle secured to said
contact arm and extending through the slot,
a conductor connected to said contact arm
and extending through the casing and tubu-
lar arm and connected to the lamp, and a
right angled extension formed on said con-
tact arm and adapted to be moved with
the arm by the handle to engage the other 25
pole of the battery.

In testimony whereof I affix my signa-
ture in presence of two witnesses.

AURA J. SANDERS.
